Jacob Steffen, St. Matthews, Ky.

Application July 25, 1938, Serial No. 221,207

4 Claims. (Cl. 197—6.1)

This invention relates to writing machines and has special reference to a typewriter for the blind.

One important object of the invention is to improve and simplify the general construction of devices of this character.

A second important object of the invention is to provide an improved construction of such a typewriter whereby the user may form Braille characters on both sides of the paper and thereby greatly decrease the cost of paper.

A third important object of the invention is to provide an improved construction of the back spacing device of such a typewriter whereby the key controlling the back spacer is so located as to be within easy and convenient reach of the operator.

A fourth important object of the invention is to improve the carriage release mechanism of such a typewriter.

A fifth important object of the invention is to the provision of a novel adjustable margin stop and guide whereby to enable the operator to use any width of paper within the maximum width for which the machine is designed and, at the same time, govern the starting point of each succeeding line so that all lines will be uniform.

A sixth important object of the invention is to provide a novel construction of the casing for the carriage return spring so that it is impossible for the user to accidentally throw the carriage out of adjustment.

A seventh important object of the invention is to provide a novel arrangement of enclosed die-punch case for prevention of dust and dirt collecting in the working parts of the dies whereby to avoid frequent repairs, cleaning and adjustment of these parts.

An eighth important object of the invention is to provide a novel arrangement of paper tension rollers adjustable for any thickness of paper.

A ninth important object of the invention is to provide a novel escapement mechanism and means for operating the same.

A tenth important object of the invention is to provide a novel arrangement of the matrix arm whereby the major portions of the back spacer and escapement mechanisms are housed beneath and protected by a portion of the matrix arm, the arm being mounted for swinging movement so as to expose the parts covered thereby when desirable or necessary.

With the above and other objects in view, as will presently be apparent, the invention con-

sists in general of certain novel details of construction and combinations of parts hereinafter fully described, illustrated in the accompanying drawings and particularly pointed out in the appended claims.

In the accompany drawings, like characters of reference indicate like parts in the several views, and:

Figure 1 is a plan view of the improved typewriter.

Figure 2 is a partial rear elevation thereof. 10

Figure 3 is an elevation of the left side of the typewriter.

Figure 4 is a fragmentary vertical section taken from front to rear of the machine and illustrating one of the keys and the die actuated thereby. 15

Figure 5 is an enlarged fragmentary rear elevation of the casing for the die bars with the cover plate removed and the die bars exposed, one bar being removed.

Figure 6 is an enlarged fragmentary section on the line 6—6 of Figure 3. 20

Figure 7 is an enlarged fragmentary plan view with certain of the parts omitted, the view disclosing the back spacer and escapement mechanisms. 25

Figure 8 is a detail plan view showing the back spacer mechanism in position to prevent movement of the carriage during formation of a Braille character.

Figure 9 is a similar detail showing the back spacer in the position assumed at the completion of the back spacing operation. 30

Figure 10 is a fragmentary section on the line 10—10 of Figure 7.

Figure 11 is a fragmentary section on the line 11—11 of Figure 7. 35

Figure 12 is a fragmentary section on the line 12—12 of Figure 7.

Figure 13 is a fragmentary section on the line 13—13 of Figure 7. 40

Figure 14 is an enlarged section on the line 14—14 of Figure 12.

Figure 15 is an enlarged bottom plan view of the escapement pawl device used herein. 45

Figure 16 is an enlarged detail section on the line 16—16 of Figure 3.

Figure 17 is an end view of the roll for holding the paper to be written upon.

Figure 18 is a transverse section through the 50 paper holding roll.

Figure 19 is a fragmentary section showing the gearing operatively connecting the paper holding roll and the paper feed rolls.

Figure 20 is a fragmentary detail showing the line stop.

The invention as herein illustrated includes a main frame indicated in general at 10. Adjacent the rear of the frame 10 is a cross-bar 11 having a depressed central portion 12. At each side of this depressed portion, the bar carries an upstanding lug or ear 13. A shaft 14 extends through the ears 13 and the ends of this shaft project. On these ends are mounted collars 15 which are secured in position on the shaft by set screws 16 thus holding the shaft in proper position in the ears. Mounted centrally on the shaft 14 is the rear end of a spacer key lever 17 which projects forwardly to lie over the front of the frame 10 and is there provided with the spacer key 18. At each side of the key 18 is a group of three character keys 19 each carried by a lever having a forward portion 20, a portion inclined inwardly from front to rear as at 21 and a rear portion 22. The front portions 20 are parallel to each other as are the portions 22. The portions 22 are pivotally mounted intermediate their ends on the shaft 14. Between the lever 17 and the adjacent lever portions 22 are washers 23 and between the several portions 22 and between the outer lever portions 22 and the ears 13 are washers 24. Thus the several levers are held in properly spaced relation on the shaft 14. The character key levers extend rearwardly and project through an opening 25 in the lower portion of the front wall 26 of a character bar casing 27. In this casing is fitted three pairs of complementary character die bars, the bars of each pair being identical in form and size but oppositely disposed. These character die bars comprise a rear pair 28, an intermediate pair 29 and a front pair 30. Each of these bars carries on its upper end a die pin 31 which, when the bar is moved upwardly, projects through a corresponding opening 32 in the top of the casing 27. The lower ends of the several die bars are arranged in staggered relation, as best seen in Figure 6, and each lower end rests on the rear end of a respective character key lever 24 so that depression of a respective key 19 protrudes a respective pin 31. Each die bar is provided with a lateral arm 32 which extends out of a cut out portion 33 in a side wall of the casing 27. Tension springs 34 have their upper ends attached to the arms 33 and have their lower ends anchored to anchor bars 35. The rear of the casing 27 is closed by a removable cover plate 36. These springs 34 serve to hold the die bars normally depressed and thus to hold the keys 19 normally raised.

Formed integrally with and extending forwardly from the collars 15 is a pair of arms 37 having their forward ends connected by a cross-bar 38 forming a spacer bar. The bar 38 is provided with a felt cushion strip 39 and extends beneath the key levers 17 and 20 so that depressing any one of the keys 18 and 19 will effect depression of the spacer bar 38. The frame 65 includes a cross bar 40. A bracket 41 having spaced and forwardly and upwardly extending arms 42 is secured to the front face of the bar 40 by screws 43. One of the screws 43 is also used to hold the upper end of a coiled tension spring 44 which has its lower end secured to the spacer bar 38 to hold the latter normally raised.

Secured to the frame sides at the upper parts thereof is a front guide bar 44 and secured to arms 45 projecting from the casing 27 is a rear guide bar 46. A carriage, indicated in general

at 47 is slidably mounted on the bars 44 and 46. Mounted on the left side of the frame 10 is a spring housing 48 containing the usual spiral spring (not shown) for rotating the housing on a shaft 49. The usual pawl and ratchet tensioning mechanism is indicated at 50 and is controlled by a knurled head 51 fixed on the shaft 49. Fixed to the carriage 47 is a ratchet bar 52 wherewith cooperates the escapement device indicated in general at 53. The escapement herein used includes a body member 54 having its forward end mounted between opposed pivot screws 55 screwed through the arms 42 and held against accidental unscrewing by the lock nuts 56. This body 54 has a bevelled nose 57 positioned for cooperation as a pawl with the ratchet bar 52. The body 54 has an angle bracket 58 formed integrally therewith and depending from the body intermediate the ends of the latter. A screw 59 extends through the body and bracket and constitutes a pivot for a laterally swinging pawl 60 having a bevelled nose 61. A coiled tension spring 62 is connected to the forward end of the pawl 60 and is anchored to a pin 63 carried by the body 54. The spring 62 normally biases the pawl 60 in the manner shown in Figures 7 and 15 and the bracket 58 limits the swinging movement of the pawl 60 in such manner that at the limit of its movement the nose 61 will align with the nose 57. Projecting forwardly from the bar 38 is a lug 64 which carries a screw 65 passing through a slot 66 in a vertical link 67. The upper end of the link 67 is secured by a screw 68 to the body 54 intermediate its ends. The screw 65 normally lies at the upper end of the slot 66. Also pivoted on the screw 65 is a second link 69 which lies alongside the link 67 and is provided with a slot 70 through which extends a screw 71 which normally engages in the bottom of the slot 70. Spaced screws 72 engage respectively in the links 67 and 69 and are connected by a spring 73 normally pulling the link 67 downwardly.

Normally the body 54 lies in an upwardly tilted position so that the pawl nose 61 engages a tooth of the ratchet bar 52. On the spring housing or casing 48 is wound a flexible strap 74 which has its end connected to the carriage 47 so that the latter is constantly spring urged to the left. Such movement is normally prevented by the engagement of the pawl nose 61. When, however, any one of the keys 18 or 19 is depressed the bar 38 will also be depressed. Consequently, the lug 64 will be depressed and carry with it the link 69. By its spring connection with the link 67 the latter will also be depressed and the body 54 will be tilted downwardly until the pawl nose 61 is freed from the ratchet bar 52. As this occurs the nose 57 will engage the same ratchet tooth as was previously engaged by the nose 61. Thus, during the downward movement of a key the carriage is held from movement to the left. When the nose 61 moves below the ratchet bar 52, the spring 62 biases the laterally swinging pawl into position for its nose 61 to engage the next succeeding ratchet tooth. When the depressed key is released the pawl body 54 tilts upwardly until its nose 57 rises to clear the ratchet bar 52 whereupon the carriage moves to the left until the nose 61, which is now engaged, assumes its normal position of alignment with the nose 57.

In order to effect release of the carriage so that it may move freely to the left, there is provided at the right of the key-bank a carriage release key 75 mounted on the forward end of a

lever 76 which is pivoted on a screw 77 fixed in the frame 10. This lever is normally held raised by a coiled tension spring 78. A plate 79 is fixed to the frame 10 and journalled in this plate and in the adjacent arm 42 (Fig. 7) is a rock-shaft 80 which carries an upwardly and forwardly extending rock arm 81 connected to the lever 76 by a link 82. The rock shaft 80 extends beneath the escapement pawls and is there provided with a rearwardly extending rock arm 83. When the key 75 is depressed the link 82 pulls the rock arm 81 downwardly and this tilts the rock arm 83 upwardly to engage and lift the escapement pawls until the nose 61 is lifted to clear the ratchet bar to allow the carriage free movement to the left. This upward tilting of the pawls is permitted since the spring 73 yields and the link 67, by its pin and slot connection with the link 69, slides upwardly with respect to the latter.

The back spacing mechanism is best seen in Figures 7 to 10. A bracket 84 is fixed on the frame 10 and extends parallel to the ratchet bar 52. Pivoted to the right hand end of this bracket is one end of a short link 85, the other end of which is pivoted to the corresponding end of a pawl bar 86 having a down turned nose 87 at its left hand end for engagement, when operated, with the teeth of the ratchet bar 52. The bracket 84 carries a pivot screw 88 spaced from the pivot of the link 85. This screw passes through a slot 89 extending longitudinally of the middle part of a lever 90. The lever 90 has its rear end pivotally connected to the pawl bar 86 adjacent the nose 87. A spring 91 has one end connected to the lever 90 and its other end connected to the frame 10 to hold the lever 90 normally biased to the position shown in Figure 7, and thus with the nose 87 normally out of engagement with the ratchet bar 52. At the left of the key-bank is a back spacer key 92 carried by a lever 93 which is pivoted as at 94 to the left side of the frame 10. A spring 94' normally holds the lever 93 raised. The lever 93 has connected thereto one end of a chain 95 which passes over an idler pulley 96 and has its other end connected to the forward end of the lever 90. When the key 92 is depressed this pulls upon the chain 95. Due to the inclined position of the lever 90, the latter is held with the screw 88 in the forward end of the slot upon pull being exerted on the chain. Upon depression of the key to a certain extent, the nose 87 will engage a tooth of the ratchet bar 52 and prevent movement to the left by the carriage 47. This condition is desirable during the formation of certain of the characters formed by the machine since it is necessary to strike certain of the keys in succession and normally this would permit action of the escapement mechanism which is undesirable. This position is shown in Figure 8.

Further depression of the key 92 will move the parts to the position shown in Figure 9 and thus carry the ratchet bar 52 and carriage 47 to the right, the pawl 60 yielding to permit this movement and acting as a check pawl upon release of the key 92. When the key 92 is released the spring 91 acts to restore the parts to the position shown in Figure 7, the slot 89 allowing the lever to slide forwardly a sufficient extent to permit the nose 87 to ride over the teeth of the ratchet bar 52.

The frame 10 is provided at each side of the key-bank with an ear 96'. A housing 97 is provided with coacting ears 98 which are pivoted to the ears 96' by screws 99 (one only shown). This housing 97 normally covers the back-spacing and

other mechanisms shown in Figure 7 and is secured in its covering or closed position by means of hook levers or latches 100 which are pivoted to the frame and engage pins 101 projecting laterally from the sides of the housing. Arching rearwardly from the housing 97 over the carriage is a matrix arm 102 carrying on its rear end a matrix head 103 having matrix recesses 104 corresponding with the die pins 31.

In the sides of the carriage 47 are supported the journal ends 105 of a paper carrying or storage roller 106. This roll is longitudinally recessed as at 107 and in this recess is mounted a paper clamp 108 which is pivoted between head plates 109 and urged to clamping position by a spring 110. Knobs 111 are secured to the journals of this roll to afford means for manually turning the same in rolling paper thereon at the beginning of writing and unrolling the paper for effecting line by line feeding across the die set. A revoluble feed roll 112 is journalled in the carriage sides and is geared to the roller 106 by suitable gearing 113. An upper feed roll 114 lies above the roll 112 and is journalled in a pair of brackets 115 fixed on a bar 116.

The bar 116 is swingingly supported by a pair of forwardly extending arms 117 pivoted to the carriage sides. Rocker levers 118 are pivoted to the carriage sides and engage the bar 116 and springs 119 urge the forward ends of these levers 118 downwardly so that the upper roller 114 is pressed firmly toward the lower roller 112. In order to raise the upper roller camming levers 120 are pivoted to the carriage sides and have cam ends 121 which engage the rear ends of levers 118 so that actuating the levers 120 in the proper direction causes the bar 116 and roller 114 to be raised. A spring pawl and ratchet device 122 is connected with the lower feed roll to insure proper spacing of lines on the paper being written upon.

A signal bell 123 is adjustably mounted at the rear of the machine for warning the user when the end of a line is approached in writing and an adjustable carriage stop 124 is mounted on the bar 46. Also an adjustable margin stop 125 is mounted on the back bar 126 of the carriage.

What is claimed, is

1. In a typewriter for the blind provided at its rear with a set of character forming elements, said typewriter further having a carriage provided with a ratchet bar, and pawl members co-operating therewith; a frame supporting the character forming elements, carriage and pawl members, a hood hinged to said frame and normally extending rearwardly from its hinge axis over said pawl members, and a character forming arm fixed to said hood and extending rearwardly over the carriage to terminate above said character forming elements.

2. In a typewriter for the blind provided at its rear with a set of character forming elements, said typewriter further having a carriage provided with a ratchet bar, and pawl members co-operating therewith; a frame supporting the character forming elements, carriage and pawl members, a hood hinged to said frame and normally extending rearwardly from its hinge axis over said pawl members, a character forming arm fixed to said hood and extending rearwardly over the carriage to terminate above said character forming elements, and latch members pivoted on said frame and engaging said hood for holding the latter closed.

3. In a typewriter for the blind having a frame

and a carriage mounted thereon for transverse sliding movement, said carriage being provided with a ratchet bar, bracket means carried by said frame in front of said ratchet bar, a back spacing pawl and escapement pawls mounted on said bracket means, a pair of hinge ears formed on said frame in front of said bracket means, a hood pivoted between said ears and normally extending rearwardly over said pawls to cover the same, 10 character forming means at the rear of said frame and a character forming arm extending centrally from the upper part of said hood and arching over said carriage in the normal position of the hood to cooperate with the character forming means.

4. In a typewriter for the blind having a frame and a carriage mounted thereon for transverse sliding movement, said carriage being provided

with a ratchet bar, bracket means carried by said frame in front of said ratchet bar, a back spacing pawl and escapement pawls mounted on said bracket means, a pair of hinge ears formed on said frame in front of said bracket means, a hood pivoted between said ears and normally extending rearwardly over said pawls to cover the same, character forming means at the rear of said frame, a character forming arm extending centrally from the upper part of said hood and 10 arching over said carriage in the normal position of the hood to cooperate with the character forming means, pins projecting from the sides of said hood rearwardly of its pivotal axis, and latch hooks pivoted on said frame to swing into 15 and out of engagement with said pins.

JACOB STEFFEN.
